177,980

CHAIR

Robert E. Kjer Jakobsen, Manhattan Beach, Calif., assignor to Virtue Bros. Mfg. Co., Los Angeles, Calif., a corporation of California

Application January 23, 1956, Serial No. 39,880

Term of patent 14 years

(Cl. D15—1)

Fig. 1 is a front elevational view of a chair, showing my new design.

Fig. 2 is a side elevational view thereof.

Fig. 3 is a perspective view to a smaller scale.

The dominant features of the design are shown in the drawing in full lines.

I claim:

The ornamental design for a chair, substantially as shown and described.
